UNITED STATES PATENT OFFICE.

GEORGE MUSCHWECK AND JOHN TUDAS, OF CARNEGIE, PENNSYLVANIA.

COAL-MINING MACHINE.

SPECIFICATION forming part of Letters Patent No. 739,335, dated September 22, 1903.

Application filed April 18, 1903. Serial No. 153,200. (No model.)

To all whom it may concern:

Be it known that we, GEORGE MUSCHWECK and JOHN TUDAS, citizens of the United States, residing at Carnegie, in the county of Allegheny and State of Pennsylvania, have invented a new and useful Improvement in Coal-Mining Machines, of which improvement the following is a specification.

This invention relates to certain new and useful improvements in coal-mining machines, and relates more particularly to that class of machines which are used for making what is known in the art of mining as "undercuts."

15 The object of this invention is to provide a machine which may be fed forward by the motor which is carried by said machine for the operation of the boring-shaft and the machine to be automatically fed laterally in front 20 of the cut.

A further object of this invention is to provide a machine wherein the operating levers or handles are located adjacently, whereby one operator may readily control and handle 25 the entire machine.

A still further object of this invention is to provide a machine which will be cheap and simple in construction, easily operated, and efficient in operation.

30 A still further object of this invention is to provide a machine that shall be short enough to pass between the face of the coal to be undercut and the first line of posts, thereby overcoming the necessity of removing said 35 posts and the material supported thereby to operate the machine.

With the above and other objects in view the invention consists in the novel construction, combination, and arrangement of parts 40 to be hereinafter more fully described, and specifically pointed out in the claims.

In describing the invention in detail reference is had to the accompanying drawings, forming a part of this specification, and 45 wherein like numerals of reference indicate like parts throughout the several views, in which—

Figure 1 is a side elevation of our improved machine in operative position for making an undercut. Fig. 2 is a plan view of the same. Fig. 3 is a detail of the jack used for anchoring the rear of the machine. Fig. 4 is a lon-

gitudinal section of the machine, showing the same mounted on the transportation-truck. Fig. 5 is a plan view of the machine. Fig. 6 is a rear elevation of the machine. Fig. 7 is a rear view of the clutch on the drive-gear of the boring-shaft. Fig. 8 is a sectional elevation of the same. Fig. 9 is an end view of the boring-shaft with a transportation-roller 60 secured thereto. Fig. 10 is a side elevation of the same. Fig. 11 is an end elevation of the brush connection on the electric-cable drum. Fig. 12 is a sectional elevation of the same. Fig. 13 is an end elevation of the 65 ratchet connection between the anchor-chain sprocket, jack-wheel, and driving-shaft. Fig. 14 is a sectional elevation of the same.

The reference - numeral 1 indicates the frame of the machine, in which the different 70 parts are mounted. A yoke 2, formed on its forward end, forms a bearing for the boring-shaft 3, said shaft passing through the cross-piece 4 5 of the frame and having at its rear the driving-gear 6, which is connected therewith by a clutch mechanism, to be hereinafter more fully described.

A motor, which may be of any well-known form, is provided within the motor-casing 7, which is secured to the side pieces of the 80 frame 1 by the feet 8, provided on said casing. The rear end of the motor-shaft has secured thereon the driving-pinion 9, which meshes with the gear 6 for driving the boring-shaft, and another pinion 10, which may be 85 formed integral with the pinion 9 or suitably secured to the driving-shaft of the motor, meshes with the gear 11, which is rotatably mounted in the cross-piece 12 of the frame, and suitably secured to said gear on the opposite side of said bearing is the worm 14, 90 which engages the worm-wheel 15, which is rotatably mounted on the axle 16 of the wheels 17 of the machine. This gear 15 is provided on one face with the notched clutch member 95 18, the other member of said clutch being keyed to the axle 16, and an angle-lever 19 for actuating said clutch extends over the side frame of the machine, and a handle is formed thereon.

The gear 15 has formed on or secured to the opposite face from that on which the clutch member 18 is located the worm 20, which meshes with a worm-gear 21, which is secured

to the shaft 22, said shaft having secured to its forward end the feed sprocket or gear 23, said sprocket being adapted when the machine is in an operative position to engage 5 the teeth or corrugations formed on a portable rack or skid 24. The rear end of the shaft 22 has keyed thereto the ratchet-wheel 25, and a jack-wheel 26, which is connected to a chain-sprocket 27, is loosely mounted 10 on said shaft and held in contact with the sprocket by the collar 28. The face of the jack-wheel which is next to the ratchet-wheel 25 has mounted thereon the spring-pressed pawl 29, said pawl being normally in 15 engagement with the teeth of the ratchet-wheel and the relation of said ratchet-wheel and pawl being such that when the shaft is turned in a predetermined direction the sprocket will also be permitted to be turned; 20 but said sprocket may be turned in a predetermined direction independent of the shaft by means of the jack-wheel.

The clutch before mentioned in connection with gear 6, which is loosely mounted on the 25 boring-shaft 3, consists in forming the outside of the end of said shaft in a square shape, as indicated by 30 in Figs. 7 and 8. An elongated cut-away portion is formed in the face of the gear, and in this cut-away portion a 30 slide 31 is adapted to operate. The said slide is provided with an aperture, which encircles the squared end of the shaft, one portion of said aperture being formed in a square to conform to the end of the shaft and the 35 other portion being circular in form and of a size sufficient to permit the squared end of the shaft to revolve therein. A spring-pressed latch is placed adjacent to the slide, and said slide is provided with notches, with which 40 this latch engages, whereby to hold the same in one of its two positions. When the slide is in a position such as shown in Figs. 7 and 8, the gear may be freely rotated without operating the boring-shaft; but should the slide 45 be moved to its other position the turning of the gear carrying said slide rotates the boring-shaft by its squared end being engaged by the squared aperture in the slide. The boring-shaft has its forward end formed in a 50 square cross-section and is slightly twisted. Suitable cutters are inserted in the apertures formed along one edge of every side, and a set-screw inserted at right angles secures the same in position. Figs. 9 and 10 show a roller 55 which may be inserted in one of these cutter-holes when the machine is moved, thereby keeping the forward end of the cutter-shaft off the ground.

The cable 33, by which electrical energy is 60 transmitted from any suitable source, is wound on a drum 34, which is rotatably mounted in the rear of the machine. Secured to one end of the shaft to which the drum is secured is the gear 35, which is engaged by 65 the pinion 36, which is operated by the cranks and handle 37 for winding or unwinding the cable. The inner end of the cable, which

is secured to the drum, has its two terminals of opposite polarity conducted to insulated rings 8, which are secured in the end of the 70 drum, and brushes contact therewith and by suitable wires are connected with the controller 40. Suitable connections between the controller and the motor permit the actuation of the same, and a reversing-switch 41 75 is provided to control the direction of the motor.

The jack, which is illustrated in Fig. 3, is for the purpose of holding the rear of the machine during its transverse movement in making an undercut, for the reason that the cutter-shaft meeting with resistance from the matter in which the undercut is being made and the power for causing the transverse movement of the machine being at the forward 85 end of the machine the same would tend to twist; but by securing the chain 42 to the hook 43 in the jack and then passing the same around the sprocket 27, as shown in Fig. 2, the rear of the machine will be held 90 back and only permitted to travel at a speed coincident with the revolutions of the shaft 22 and sprocket 23.

The transportation-truck, on which the machine may rest when being moved, consists 95 of a platform 44, having extensions on either forward side, and guard-rails 45 being provided on either side the length thereof. This platform is mounted on suitable wheels, and a loop at the rear and a removable chain at 100 the forward end form a place to hook onto the same to drag it about.

While we have shown and described our invention in detail as practiced by us, yet it will be obvious that various slight changes 105 may be made in the details of construction without departing from the general spirit of our invention.

Having fully described our invention, what we claim as new, and desire to secure by Letters Patent, is—

1. In a machine of the character described, the combination of a frame mounted on a suitable truck, a boring-shaft rotatably mounted in said frame and carrying a series of adjustable cutters, a shaft mounted in said frame having at one end a toothed wheel adapted to engage some fixed surface for the purpose of moving the machine when said shaft is revolved, the other end of shaft having a 115 sprocket connected therewith through a ratchet and pawl, a chain adapted to be passed over said sprocket, one end of the same being anchored, thereby to retard the movement of the machine, a motor mounted in said frame 120 and suitably geared to the boring-shaft, the shaft for moving the entire machine laterally and the axle of the truck, substantially as described.

2. In a machine of the character described, 130 the combination of a frame mounted on a suitable truck, a boring-shaft rotatably mounted thereon, the outer end of said shaft being squared and twisted into a spiral, a plurality

of adjustable cutters mounted in said squared portion of the boring-shaft, a motor having a gear connection with said boring-shaft, a clutch for disengaging said gear connection, 5 a geared connection between said motor and the axle of the truck whereby the machine may be moved, a clutch for disengaging said geared connection, a shaft mounted in said frame, a toothed wheel mounted on one end 10 thereof and adapted to engage a stationary surface whereby to give lateral movement to the machine when said shaft is revolved, geared connections between the said motor and the said shaft whereby the shaft may be 15 revolved, a sprocket loosely mounted on said shaft and carrying a pawl, a ratchet secured

to said shaft and engaged by said pawl, means mounted on the frame of the machine for actuating the motor, a drum mounted in said frame, an electric cable one end of which is 20 secured to said drum, connections through brush and ring, connections between said cable and the means for controlling the motor, and means for revolving said drum.

In testimony whereof we have hereunto 25 signed our names in the presence of two subscribing witnesses.

GEORGE MUSCHWECK.

JOHN TUDAS.
